CLAIM

The ornamental design for a housing for communications equipment as shown and described.

DESCRIPTION

FIG. 1 is a front perspective view of a first embodiment of a housing for communications equipment showing our new, original, and ornamental design;

FIG. 2 is a front view of the housing for communications equipment of FIG. 1;

FIG. 3 is a rear view of the housing for communications equipment of FIG. 1;

FIG. 4 is a left side view of the housing for communications equipment of FIG. 1;

FIG. 5 is a right side view of the housing for communications equipment of FIG. 1;

FIG. 6 is a top view of the housing for communications equipment of FIG. 1;

FIG. 7 is a front perspective view of a second embodiment of a housing for communications equipment showing our new, original, and ornamental design;

FIG. 8 is a front view of the housing for communications equipment of FIG. 7;

FIG. 9 is a rear view of the housing for communications equipment of FIG. 7;

FIG. 10 is a left side view of the housing for communications equipment of FIG. 7;

FIG. 11 is a right side view of the housing for communications equipment of FIG. 7; and,

FIG. 12 is a top view of the housing for communications equipment of FIG. 7.

The broken lines depict portions of the article that form no part of the claimed design.

1 Claim, 12 Drawing Sheets
